UNITED STATES PATENT OFFICE.

DANIEL A. SUTHERLAND, OF LYNN, MASSACHUSETTS.

PRESSER-FOOT FOR SEWING-MACHINES.

SPECIFICATION forming part of Letters Patent No. 381,090, dated April 10, 1888.

Application filed May 5, 1887. Serial No. 237,196. (No model.)

To all whom it may concern:

Be it known that I, DANIEL A. SUTHERLAND, of Lynn, in the county of Essex and Commonwealth of Massachusetts, have invented certain Improvements in Sewing Machine Presser-Feet, of which the following, taken in connection with the accompanying drawings, is a specification.

Referring to the drawings, Figure 1 is a perspective view representing my improved presser-foot and a piece of material, the design being to represent the operation of the foot. Fig. 2 is a rear elevation of the foot; and Fig. 3 is a plan of the bottom of the foot, Figs. 2 and 3 being on an enlarged scale.

This presser-foot is designed particularly for use in making corrugated seams in boots and shoes and other leather and textile materials, which seams have already been patented to me by Letters Patent of the United States, dated July 30, 1878, No. 206,641. To this end I take an ordinary presser-foot, A, having needle-hole *a* and adapted to be attached to the presser-foot bar of an ordinary sewing machine. The bottom face of the foot is provided with channel-grooves *e e* and the intermediate fin, *f*. The channels are intended to receive the corrugations *h* of the seam, while the fin *f* is allowed to enter the seam-crease *n*, all as shown in Fig. 1. The side bars, *m*, of the foot are extended downward below the bottom of the fin *f* and are allowed to bear upon the material on either side of the ribs, to the end that the ribs or corrugations *h* may be crowded well up into the grooves *e* and held therein during the operation of sewing through the material and stay-piece. I am aware that presser-feet have been heretofore constructed with a central fin to enter a seam-crease and

guide the material along while being stayed; but in the feet heretofore used the central fin has been the prominent feature. It is commonly depressed or projected below the side bars of the foot to enter and guide the material; but in my foot the side bars, *m*, are made 45 the prominent parts and are extended below the central fin, the purpose of the fin being not to guide the material but to simply open the seam-crease while being sewed—that is, while the stay-piece is being sewed on. 50

It will be understood that the corrugations *h* are formed in the material first and the foot is designed to hold the corrugations in shape and in position relatively to each other while the operation of sewing on the stay-strip *t* is being performed. 55

I am also aware that a presser-foot has been heretofore constructed with a groove adapted to receive a welt, and with a recess formed in the undersurface of said foot to allow the passage of several thicknesses of material which are connected with the welt, and I do not broadly claim this as my invention. 60

I claim and desire by Letters Patent to secure—

As a new article of manufacture, a presser-foot made in one piece with two semicircular grooves or channels, *e e*, arranged parallel throughout the under surface of the presser-foot, the central fin, *f*, dividing the channels, 70 and the lateral side projections, *m m*, extending below the bottom surface of the central fin, substantially as described.

DANIEL A. SUTHERLAND.
